RAZOR BLADE PACKAGE

William H. Hoogs, Honolulu, Territory of Hawaii,
assignor of two-fifths to William A. Ramsay,
Honolulu, Territory of Hawaii

Application August 17, 1933, Serial No. 685,557

7 Claims. (Cl. 206—46)

My invention relates to razor blade packages or containers, more particularly to packages for safety razor blades, and has for its object a buoyant package by means of which the used 5 blades can be readily disposed of.

The problem of disposal of used safety razor blades has heretofore been a perplexing one. The blades are ordinarily sold in paper packages, usually with individual envelopes for the blades. 10 These envelopes are customarily destroyed in removing the blades, but even if preserved give little protection for the blade and little aid in the disposal of the blade when used. It will be understood that the used blade, even though 15 too dull to serve its purpose, is still very sharp in the common meaning of the term, and hence a menace to adults as well as children if not safely disposed of.

It is an object of my invention to provide 20 a package or container in which the new blade may be sold, as well as a package of substantial construction which can be used with safety in the disposal of the used blade. One of the fundamental features of my package is that it is sufficiently buoyant to float the blade in water. The 25 package is furthermore arranged so that when a new blade is removed, the old blade can easily be inserted in its place. The package containing the old blade can then readily be disposed of by throwing it into the drain. If the buoyant 30 package were not used, the blade would of course sink to the bottom of the drain and remain there.

For a more complete understanding of the invention reference should be had to the accompanying drawing, Fig. 1 of which is a perspective view of a razor blade package embodying my invention and containing a new blade; Fig. 2 is a view similar to Fig. 1 but showing a used 35 blade partially inserted in the package; Fig. 3 is a fragmentary side elevation view showing a used blade inserted in the package; while Fig. 4 is a section view along the line 4—4 of Fig. 3 looking in the direction of the arrows.

Referring to the drawing, I have shown my package or container in one form as comprising 40 two rectangular plates or boards 10 and 11 made of a suitable rigid buoyant material, such as a light veneer wood. The two plates 10 and 11 have roughly the general outline of the razor 45 blade 12 inserted between them, indicated by the dotted lines, but are somewhat larger, and they have sufficient combined volume or mass to float the blade in water. They are secured tightly together, with their sides adjacent, as

shown in the drawing, by a strong paper wrapper 13 surrounding them, and having its ends glued together. Preferably the wrapper 13 is made from paper having considerable strength, and which is resistant to water to a considerable degree, such as heavy brown wrapping paper. If desired the paper may be suitably waterproofed so as to be resistant to water, as by a coating of shellac, which protects also the glued ends of the paper. The point is that the package is 10 constructed so that it does not readily disintegrate when dropped in water, and therefore carries the used blade to a permanent place of disposal. Preferably also the wrapper 13 surrounds the sides and edges having the greater dimensions, leaving at least one end open for the insertion of a razor blade between the plates. The opposite end may and preferably is closed by the wrapper. Not only are the plates sufficiently thick to give the volume necessary to float 20 the blade, but they are also thick enough to have the required rigidity to be self-sustaining when the tight wrapper 13 is applied to them.

This package when sold contains a new blade 12, as shown, which blade is inserted in the 25 package between the two ends 14 and 15 of a strip of paper by means of which the blade can easily be removed. In other words the strip of paper of desired length is folded at the middle, the blade placed between the two ends of the paper, 30 with one end of the blade against the fold 16, and then the blade is slipped in place between the plates 10 and 11. The two ends 14 and 15 of the paper protrude for a sufficient distance 35 from the plates, such as one-half inch, to allow their being securely grasped with the fingers and pulled to remove the new blade from the package. Since the plates are held tightly together by the outer wrapper 13, as previously stated, it would be very difficult, if not impossible, to withdraw the blade unless some suitable means such as the strip of paper were provided to facilitate 40 its removal. It is furthermore contemplated that the new blade is thus easily removable without the necessity of breaking the wrapper 13. In 45 fact the removal of the new blade is thus facilitated to such an extent that there is no need nor desire to break the wrapper, so that the package is preserved intact for the disposal of the used blade.

It will be understood that the package containing the new blade may not be assembled in the steps indicated. For example, the new blade, the strip of paper and the two plates may be assembled together in the relation described and 55

then the paper wrapper 18 applied tightly around the plates.

Upon the removal of the new blade it is contemplated that the used blade just removed from the razor, will be inserted in the package in place of the new one but without using the strip of paper, which is destroyed. Fig. 2 shows the old blade 17 partially inserted between the two buoyant plates. For the purpose of facilitating the insertion of the old blade one of the plates is preferably made slightly longer than the other. As shown the plate 11 is somewhat longer so that it projects beyond the plate 10 for a short distance such as $\frac{1}{8}$ or $\frac{1}{4}$ of an inch. This projecting end definitely defines one plate from the other at their ends, and hence the space between the plates, so that the used blade may be easily inserted by placing its end against the side of the projecting end of the plate 11. The used blade is then pushed in between the plates as far as possible with the fingers, preferably until its outer end is substantially flush with the end of the shorter plate 10, as shown in Fig. 3. It is then practically impossible to remove the blade without destroying the package. The end of the blade cannot be grasped with the fingers, and even if it could be grasped to a limited extent the blade could not be pulled out, since it is held between the plates with very considerable friction. Furthermore the projecting end of the longer plate 11 serves also as a shield for the outer end of the inserted blade.

As shown in the drawing, the blade whether new or old is preferably positioned with its cutting edges midway between the two adjacent side edges of the plates. When thus arranged the plates project at each side beyond the cutting edges, as shown, so as to protect the cutting edges from damage in handling when the blade is new, and to prevent accidental contact with the edges when the blade is to be thrown away. The rigid substantial construction of the plates affords ample protection from the edges of the blade. While a double edge type blade is shown in the drawing it will be understood that my invention is applicable to the single edge type of blade as well.

It will be observed that the projecting ends 14 and 15 of the strip of paper give a reliable indication as to whether the package contains a new or old blade. It is contemplated however that the used blade will be inserted in the package, while the blades are being changed, as soon as the new blade has been removed, and then the package containing the old blade immediately disposed of permanently by flushing it down the drain. Obviously this package may also be thrown with safety into a waste paper basket or garbage can.

While I have shown a particular embodiment of my invention, it will be understood, of course, that I do not wish to be limited thereto since many modifications may be made, and I therefore contemplate by the appended claims to cover any such modifications as fall within the true spirit and scope of my invention.

What I claim as new and desire to secure by Letters Patent of the United States is:

1. A floating razor blade container comprising buoyant means having a volume sufficient to float said blade, and means resistant to water for attaching a blade to said buoyant means and for covering a cutting edge of said blade, said attaching means being resistant to water to at least such an extent that said buoyant means serves to convey the blade to a place of disposal. 10

2. A floating package for razor blades comprising plate means made of buoyant material having the general outline of the blade but somewhat larger, said plate means having sufficient volume to float the blade, and wrapping means 15 for securing the blade to said plate means, said package being resistant to water to at least such an extent as to convey the blade to a place of disposal.

3. A floating razor blade container comprising plate means made of buoyant material somewhat larger in outline than the blade having sufficient volume to float the blade, and wrapping means surrounding said plate means, said wrapping means being resistant to water to at least such an extent that said plate means serves to convey the blade to a place of disposal. 20

4. A floating razor blade container comprising a pair of plates made of buoyant material somewhat larger in outline than the blade and having sufficient volume to float the blade, and wrapping means for securing said plates tightly together with at least one edge exposed so as to provide for the insertion of a blade between them, said wrapping means being resistant to water to at least such an extent that said plates serve to convey the blade to a place of disposal. 30

5. A floating razor blade container comprising a pair of plates made of buoyant material somewhat larger in outline than the blade and having sufficient volume to float the blade, and wrapping means for securing said plates together in such manner that a blade may be inserted between and thereby secured between said plates, one of said plates being somewhat longer than the other to provide a projecting end to facilitate the insertion of the blade between them. 40

6. A floating razor-blade container comprising buoyant means having a volume sufficient to float the blade in water, and means for securing the blade to said buoyant means, said container being resistant to water to at least such an extent as to convey the blade to a place of disposal. 50

7. A floating razor-blade container comprising a rectangular plate of buoyant material somewhat larger in outline than the blade, a wrapper surrounding two parallel edges of said plate to thereby provide for the insertion of a blade through one of the remaining edges of the package thus formed, said wrapper being arranged to secure the blade tightly to said plate and being resistant to water to at least such an extent that the package serves to convey the blade to a place of disposal. 55
